Edward N. Pageau,

ATTORNEY.

UNITED STATES PATENT OFFICE.

CLARENCE E. BARR, OF DETROIT, MICHIGAN, ASSIGNOR OF ONE-FOURTH TO FLORENCE KING ALLEN, ONE-FOURTH TO WILLIAM M. MERVIN, AND ONE-HALF TO THOMAS E. JACKSON, ALL OF DETROIT, MICHIGAN.

ELECTRIC HEATER.

Application filed April 18, 1921. Serial No. 462,130.

To all whom it may concern:

Be it known that I, CLARENCE E. BARR, a citizen of the United States, and residing at Detroit, in the county of Wayne and 5 State of Michigan, have invented a new and Improved Electric Heater, of which the following is a specification.

This invention relates to portable electric heaters of relatively small size in which the 10 heating element is entirely enclosed, and its object is to provide a device of this character which is simple in construction, of good heating capacity, and which is not liable to get out of order.

15 This invention consists of a shell and a perforated top and bottom therefor, of a series of upright supports of non-conducting material such as asbestos board which is little affected by heat, said supports being connected at their inner edges and notched along their outer edges, and resistance wire wound around in the notches at the top and following around in the notches down the side edges of the supports.

20 25 It further consists in the details of construction illustrated in the accompanying drawing and particularly pointed out in the claims.

In the drawing, Fig. 1 is an elevation of 30 the supports for the heating wire and a central vertical section of the shell of this improved heater. Fig. 2 is a section of the heater on the line 2—2 of Fig. 1. Fig. 3 is a plan of the wire supports. Fig. 4 is 35 a perspective of a preferred connector for the wire supports.

Similar reference characters refer to like parts throughout the several views.

The shell 1 of this heater is preferably 40 cylindrical and united to the perforated top 2 by any desired means, small bolts 3 extending through the shell and the flange 4 of the head being shown. A perforated base 5 formed with legs 6 and a flange 7 may 45 be secured to the shell by the screws 8. Any desired number of perforations of any desired size and shape may be formed in the head and bottom, but I prefer to form the perforations 9 in the bottom of somewhat 50 more total area than the perforations 10 in the top.

While any desired number of supports 12 may be employed I prefer four and I

prefer to secure them radially together by means of the connectors formed of pairs of 55 leaves 13 united at their middle points and formed with struck-up tongues 14 adapted to extend through holes in the supports 12, as shown in Fig. 2, and with the ends of these tongues bent down against the supports to hold them in position. The outer 60 upright edges of these supports are preferably concave.

The outer vertical edges and the top 65 edges of these supports are formed with the notches 15 and 16 to receive the coiled resistance wire 18, which is preferably looped in the notches 16^a (Fig. 3) intermediate its ends, then wound around in the upper notches 16 and then wound around in the 70 side notches 15 until its ends are attached to the binding screws 19 and 20. A cable 22 has its wires 23 and 24 attached to these binding screws to supply current to the resistance wire.

75 It will be noticed that the greater portion of heating wire is in the upper part of the heater, which is also where the hottest air is found. The ascending cold air takes up heat from the lower windings, but the 80 desired high temperature is imparted to the air by the more closely wound coils at the upper ends of the supports. Because of the concave outer edges of the supports, there is 85 less possibility of air passing up without being heated.

The sizes, proportions and details of the various parts of this heater may all be 90 changed by those skilled in the art without departing from the spirit of my invention as set forth in the following claims.

I claim:—

1. In a heater, the combination of a cylindrical shell, a perforated top and bottom therefor, a series of radial supports of non-conducting material within the shell having notches in their outer vertical edges, and a coiled heating wire wound around the support and held in these notches, the outer upright edges of the supports being 100 concave.

2. In an electric heater, the combination of a shell, a top and a bottom therefor, a series of flat supports of non-conducting material radially arranged and connectors between them, said supports having notches in 105

their outer upright edges and top edges, a heating wire wound around in said upper and side edges, binding screws mounted in said supports to which the lower ends of the 5 heating wire are attached, and conductors for electric current attached to said screws.

3. In a heater, the combination of a series

of supports of non-conducting material attached to each other so as to extend from a common vertical axis and having concave 10 edges provided with notches, and a heating element wound into said notches.

CLARENCE E. BARR.
